UNITED STATES PATENT OFFICE.

CLAUDE DÉSIRÉ GOUBET, OF PARIS, FRANCE.

SUBMARINE TORPEDO-BOAT.

SPECIFICATION forming part of Letters Patent No. 352,124, dated November 9, 1886.

Application filed November 27, 1885. Serial No. 184,078. (No model.)

To all whom it may concern:

Be it known that I, CLAUDE DÉSIRÉ GOUBET, a citizen of the French Republic, and a resident of Paris, France, have invented certain Improvements in Submarine Torpedo-Boats, of which the following is a specification.

My invention relates to that class of torpedo-boats for naval warfare which are designed to run under water; and the principal object 10 of my invention is to increase the stability of the boat when submerged.

One of the principal obstacles to the movement of submarine boats is their lack of stability. Indeed, when a boat is completely submerged its equilibrium may be destroyed by 15 the least displacement of the interior weight. By reason of the velocity required the displacements of the boat are accentuated in ascending or descending, according to the angle 20 of inclination.

I realize perfect equilibrium of the boat by means of my construction, which I will now describe with reference to the accompanying drawings, wherein—

25 Figure 1° is a longitudinal vertical section of my improved torpedo-boat, and Fig. 2° is a plan, with the shell partly broken away to show the interior. Fig. 1 is a view of the screw-propeller-driving mechanism detached, 30 and illustrating how it may be driven by hand through the medium of cranks. Figs. 2 and 3 are respectively a side elevation and plan on a larger scale, showing the screw and the mechanism for shifting the angle of its axis of 35 rotation. Figs. 4 and 5 are views showing a mechanism detached and enlarged for illustrating the principle of preserving the equilibrium of the boat when submerged. Fig. 4 is in elevation at the left and in section at the 40 right. Fig. 5 is a central transverse section of Fig. 4. Figs. 6 and 7 are detached and enlarged fragmentary views designed to illustrate the mode of mounting oars on the sides of the boat, to be operated from the inside. 45 This device may be denominated an "hermetic rowlock." Figs. 8, 9, and 10 are geometrical diagrams illustrating the form of the boat. Fig. 11 is an enlarged and detached view illustrating the preferred form of friction-clutch 50 employed.

Referring first to Figs. 1° and 2°, it will be seen that the boat has a cigar shape and is de-

signed to be propelled by a screw, W, which may be driven by a motor, M, as seen in Fig. 1°, or by cranks, as seen in Fig. 1; or in case 55 of injury to the screw or its driving mechanism, the boat may be propelled by oars X. In the bottom of the boat are formed tight water-chambers h h', supplied by pipes from a three-way cock, P, which admits water to 60 either or both of these chambers, as desired. A pump, c, driven by motor M, serves to remove the water from these chambers. On the chambers h h' is mounted the compressed-air chamber b, and on this chamber are the seats 65 for the officer and steersman, who form the entire crew. On the top of the boat is a dome, the cap a of which is hinged and removable to admit the crew. The margin of this cap rests on a rubber ring in a channel, 10, to form an 70 air-tight joint. The admission of air to the boat from chamber b is controlled by a valve, e, Fig. 2°. The air passes first to chambers h h' by a pipe, J, whereby it is moistened, and it escapes thence to the interior of the boat by 75 a pipe, k, which discharges in the dome near the level of the heads of the crew. The viti- 80 ated air is removed by an air-pump, d.

The "trimming" device whereby the equilibrium of the boat is maintained will now be described.

A is a pendulum suspended in the center of the boat and connected to a clutch-shifting bar, 4, which acts, when the pendulum swings, to shift a clutch, 5, so as to set a double pump, 85 V, (seen in plan in Fig. 2°,) in motion, either to the right or left, depending on which way the boat inclines with respect to the pendulum A. This pump V is connected by pipes (not shown) with two reservoirs, A' and A'', 90 one in the stern and the other in the bow of the boat, in such a manner that when running in one direction the pump will force water from reservoir A' to reservoir A'', and when its motion is reversed it will force the water 95 from A'' to A'. When the boat sinks at the bow, the pendulum A will swing in that direction, and through bar 4 shift the clutch 5, so as to set pump V in motion to pump water from reservoir A'' to reservoir A'. When the boat 100 sinks at the stern, pendulum A swings in that direction and sets pump V to work to force water from A' to A''. In point of fact, the action is so quick and the pump so powerful that-

the boat will be righted before it can reach any considerable degree of inclination, and in practice this governing device will always maintain it in a horizontal position, or on an 5 "even keel," whatever may be the depth at which it may be submerged.

The boat is provided with a weight or mass of metal, X', on its bottom to serve as ballast. This weight is fixed to the boat by a bolt, g, 10 on the lower end of which is screwed a nut, 6, which rests in a recess in the weight, X'. The bolt g, in entering the boat, passes through a box, 8, fixed to the boat-bottom and provided with a conical seat to receive a cone, 7, on the 15 bolt. This prevents leakage around the bolt. On its upper end the bolt g has a suitable head, as shown in Fig. 1°.

The boat is submerged by allowing water to flow in and fill the partitioned reservoirs h h', 20 and it is brought to the surface again by expelling this water by means of the pump c; but should the pump break down or fail to operate from any cause, it will be sufficient to turn the screw g by any means, and this will 25 run off the nut 6 from its lower end and permit the weight X' to fall off. The boat will then rise to the surface, despite the water in chambers h h'.

The motor M, which drives the screw-propeller and the several pumps, is an electric motor, and the electro-motive force is furnished by accumulators stowed in lockers in the forward part of the boat, as seen in Fig. 1°.

My boat is provided with a screw-propeller, 35 W, driven from the motor through a universal joint, whereby the axis of the propeller-shaft may be made to assume an angle, laterally, with the axis of the boat. This enables me to steer the boat without the aid of a rudder. The 40 mode of mounting the propeller and changing the angle of its shaft in order to steer the boat, will now be described with reference to Figs. 2 and 3, wherein W is the screw-propeller, the shaft of which has a long bearing in a frame, B. 45 This frame B is hinged at C C to two links, D D, which links are hinged at E E to a stern-piece on the boat. The propeller-shaft is coupled to the motor-shaft F by a universal joint, G, and the jaws in which the links D D are coupled are 50 toothed at H H, so as to compel the frame B, carrying the propeller, to swing on the axis of the joint G. The inner end of the upper links, D, is provided with teeth like a toothed gear-wheel, and these teeth mesh with the thread on 55 a worm or screw, H', which is rotated by means of a chain and sprocket-wheels from a steering-wheel, m, under control of one of the crew, as seen in Fig. 1°. Thus, the propeller may be 60 swung from side to side on its hanging axis in the same manner as a rudder.

Referring now again to Fig. 1°, S represents a long fixed bearing for the motor-shaft, with suitable packing to prevent entrance of water. The motor-shaft is divided or cut inside the 65 clutch-sleeve 12, the sleeve being splined on the motor part or end of the shaft. The miter-wheel 13 is loosely mounted on this part of the

shaft. The miter-wheel 14 is keyed on the propeller part of the shaft. The intermediate wheel, 15, is mounted loosely on a bearing below. By shifting the clutch-sleeve the propeller may be arrested, or may be made to revolve in either direction. This is effected by means of a reversing-lever, u, which connects (see Fig. 2°) by a bar, 16, with the shifting lever or 75 fork.

My boat is managed as follows: The officer and sailor descend into the boat at the dome, which is afterward closed hermetically by the cap or hinged cover a. The dome is provided with glazed peep-holes in front of the men, which holes are protected by gratings, and have wickets or caps, whereby they may be quickly closed in the event of the glass being broken. The torpedo Y is mounted on the boat 80 back of the dome and is connected by a bayonet-fastening, detachable from the inside. It is connected to an electric exploding-wire wound on a drum, 11, and connected with the electric source by means of a commutator. The pressure of air in the boat or shell, and in the reservoir, is indicated by manometers.

Before submerging the boat the officer sights the object to be attained, (as a vessel of the enemy, for example,) getting the proper alignment with the aid of the mast or "jack-staff" U. (Seen in Fig. 1°.) When properly headed for the object, he notes the bearing on the compass O placed directly before him. This observation made, he opens the cock P, which 95 admits water to the reservoirs h h'. This sinks the boat below the surface, and when it has reached the proper depth, as indicated by a manometer, s, in the dome, he closes the cock P, and directs the boat by the compass toward 100 the object to be attained. When the boat has reached the vessel, which can be ascertained very readily through a glazed aperture in the cap a of the dome, the boat may be maneuvered to secure the best position, and may 105 be made to ascend or descend by operating the lever r, Fig. 1°, which controls the clutch which connects the pump c with the motor. When the proper position under the vessel has been reached, the torpedo Y is liberated. 110 It rises in the water, and the points on its crown fix themselves in the bottom of the vessel to a sufficient extent to hold it in position. When the torpedo has been set free, the wire from the reel or drum 11, Fig. 1°, is payed out 115 or unwound as the boat moves off, the revolutions of the drum indicating to the pilot the distance moved. When the boat has moved away a distance of from one hundred to one hundred and fifty meters, the electric circuit 120 is closed and the torpedo exploded.

Referring now to Figs. 4 and 5, which are designed to illustrate the principle of my device for maintaining the equilibrium of the boat automatically, I is a receptacle or housing which is supposed to be placed in the center of the boat, and K K' are two tubes or hollow arms, bearing at their ends, respectively, the globular reservoirs N N'. Pipes Q Q, re- 130

spectively, connect these reservoirs with a double pump, R, arranged in the receptacle I. This pump is of such a character that when revolving in one direction it will force the 5 water from reservoir N to reservoir N', and when revolving in the other direction it will operate inversely and force the water from N' to N. The pump is driven from a shaft, 1, arranged below it, on which are loosely mounted 10 two bevel-wheels, 2 2'. These mesh with another bevel-wheel, 3, which is driven constantly by a spring-motor. (Not shown in the drawings.) The shaft 1 is not rotated, except when one of said bevel-wheels, 2 or 2', is made 15 solid with the shaft, and this is effected by means of a clutch, f, splined on the said shaft and arranged to slide into and out of engagement with the wheels 2 2'. This clutch f is controlled by a pendulum-lever, i, on which 20 is a pendulum, n.

The operation is simple. When the apparatus is inclined—so as to lower the reservoir N, for example—the pendulum swings toward N and sets the pump R in motion to 25 pump water from reservoir N to N', thus restoring the equilibrium. Weights may be suspended from the reservoirs to test the apparatus, which may be suspended from the pivotal point of suspension of the lever i.

30 The boat is supplied with oars for hand propulsion, as before stated. These are seen in Figs. 1° and 2°.

In Figs. 6 and 7 I have shown on a larger scale the construction whereby the oars may 35 be operated from the inside of the boat and leakage of water is prevented. Referring to these figures, Fig. 6 is a section through the side of the boat in the plane of the oar and Fig. 7 is an exterior elevation. o represents 40 the handle or arm of an oar which projects within the boat through an opening in its sides, and p is the hinging-fork of the oar exterior to the boat. Both of these are fixed to a pivotal bolt or axis, q, which has bearings 45 in a housing, j, bolted to the outer side of the boat. Where the axis q passes through the upper and lower sides of the casing or housing j, it passes through packed apertures or stuffing-boxes, as clearly shown, whereby leakage is 50 prevented. The blade of the oar is composed of movable wings, which close on each other when the blade is forced backward, but which open when the blade is moved forward. This 55 construction I have not shown, as it is not important.

In Fig. 1 I have shown an adaptation to the propeller-shaft of cranks, whereby the two men may propel the boat. This is a simple application of cranks and gear-wheels, and will 60 require no detailed description.

In Fig. 11 I have shown the form of automatic clutch I prefer to employ. This clutch comprises a cone, l, splined on the shaft, and a conical plate or disk, t, fixed on the shaft. 65 This latter may be a pulley or toothed wheel. The cone l is forced up to the disk t by a spring which abuts against a ring, v. The

tension of the spring is regulated by making the ring v movable on a collar, w, fixed on a shaft. The cone l has recesses y, in which 70 rest the hook-like heads on the splines, which latter terminate at z and are connected to the grooved collar z. By actuating this collar by means of the fork I one can engage or disengage the clutch; but the force exerted by the 75 flanges of the grooves Z on the fork is considerable. To relieve the strain I hold the collar z in its disconnected position by latches 4 4, which are hinged to z, and hook over a collar, H, fixed on the shaft. A counter-lever, 80 Σ, is coupled to and moves a ring, Ω. When the latter is moved to the left, it raises the latches 4 4, the collar z is freed, and the spring presses the cone z up to the disk t. This device permits, as may be seen, the regulation at 85 will of the pressure of cone l on disk t. The retaining-latches prevent the friction that would be brought on the rollers in the fork of lever I in holding the cone out of engagement against the tension of the spring. 90

Referring, now, to Figs. 1° and 2°, it will be seen that the boat is provided at its prow with a lance or pike, s', which may be projected by means of a lever, T. This lance plays in and through a ball-and-socket bearing 95 in the prow of the boat, whereby it is capable of being vibrated in all directions, as well as moved lengthwise. This serves to cut the wires of any torpedoes placed in the path of the boat and the field in which the lance s' plays. The 100 path of the boat may be illuminated by means of an incandescent electric light, as clearly shown.

In order that the boat may make known its 105 position by signals, a vertical tube, Z, is fixed in the upper part of the shell, Fig. 1°, and provided with two wickets or gates, one above the other, and operated by very simple mechanism. This forms a sort of lock. The upper gate being closed and the lower gate opened, 110 a signal-cartridge is inserted and the lower gate closed. The upper gate being now opened, the cartridge rises by virtue of its feeble specific gravity. Its construction is such that when it reaches the surface of the water it ignites, and the explosion will notify the vessel or the port to which the boat belongs. Colored fires may be sent to the surface in the 115 same way to indicate the depth of the boat and its position. A buoy, carrying a telephone, 120 may be launched from the boat, whereby the crew of the boat may be communicated with from the outside.

As showing the present state of the art, I may say that I am aware that submarine torpedo-boats have before been provided with detachable weights or keels, with domes having glazed peep-holes, with screws or propellers mounted on universal joints for steering, with water-chambers and pumps for water-logging, and 125 with means whereby an occupant of the boat, clad in a diver's suit, may get outside of the boat while it is submerged. Therefore I do not claim these features. 130

Having thus described my invention, I claim—

1. A submarine torpedo-boat having reservoirs at bow and stern containing a liquid, and means automatically controlled by a pendulum for transferring the liquid or a portion thereof from one reservoir to the other, in order to preserve the equilibrium of the boat.
2. A submarine torpedo-boat provided with reservoirs of liquid at its bow and stern, pipes connecting these reservoirs with a pump, mechanism, substantially as described, for operating said pump, a shifting mechanism for changing the motion of said pump, and a pendulum connected with said shifting mechanism, whereby said pendulum automatically controls the motion of said pump, substantially as set forth.
3. A submarine torpedo-boat provided with a water-reservoir in its bottom, a cock for admitting water to said reservoir to submerge the boat, a motor for expelling the water from said reservoir to permit the boat to rise, reservoirs at the bow and stern to contain a liquid, and means, automatically controlled by a pendulum, for transferring the liquid in whole or in part from one of these latter reservoirs to the other to trim the boat or preserve its equilibrium, as set forth.
4. A submarine torpedo-boat provided with a weight, X, carrying a nut, and a rotating bolt, y, extending down through the boat-bottom and screwed into said nut, said bolt having a head on its inner end, and a cone, 7, fitting into a seat, whereby the bolt is stopped from endwise movement, leakage is prevented, and the weight made detachable from inside the boat, as set forth.

5. The combination, with the propeller and its shaft, of the hinged frame in which said shaft is mounted, the motor-shaft, the universal joint which couples the two shafts, the hinging-links, toothed as shown, and the screw or worm which meshes with the teeth of one of the links, substantially as set forth. 45

6. A submarine torpedo-boat provided with housings j, mounted exteriorly on its sides and provided with packed bearings in which are mounted axes q, to which are secured the arms o of the oars, and the oars, with their hinging-forks p, attached to the exterior ends of said axes q, substantially as and for the purpose set forth. 50

7. A submarine torpedo-boat provided with a rotatively-mounted spindle arranged vertically in its roof, with a bayonet-fastening on its outer extremity whereby the torpedo is secured thereto, and means for rotating said spindle from inside the boat in order to release the torpedo therefrom, as set forth. 55

8. A submarine torpedo-boat provided with a lance, s', at its prow mounted to play through a ball-and-socket bearing in the prow of the boat, whereby the said lance may be protruded and vibrated laterally and vertically, and an electric lamp on the prow to illuminate the field in which said lance vibrates, substantially as and for the purposes set forth. 60

In witness whereof I have hereunto signed my name in the presence of two subscribing witnesses. 70
